UNITED STATES PATENT OFFICE.

GEORGE N. FREY, OF PASADENA, CALIFORNIA.

CIRCUIT-BREAKER TERMINAL.

1,332,172.

Specification of Letters Patent. Patented Feb. 24, 1920.

Application filed October 16, 1918, Serial No. 258,476. Renewed January 17, 1920. Serial No. 352,243.

To all whom it may concern:

Be it known that I, GEORGE N. FREY, a citizen of the United States, residing at Pasadena, in the county of Los Angeles, 5 State of California, have invented certain new and useful Improvements in Circuit-Breaker Terminals, of which the following is a specification.

My invention relates primarily to a circuit breaker terminal for use in the overhead power lines of electric railways and has for its object the provision of means for easily and quickly positioning the end of the wire therein and which will positively 15 retain the same in its position of use thus obviating the possibility of accident through the wire becoming accidentally loosened.

A further object is to provide a device of that character which, when used in a continuous transmission or supply line of electric railways, will connect or form a continuation of the trolley wire thereby minimizing the danger of the trolley wheel of the car leaving the wire while making the 25 crossing.

Other objects and advantages will appear hereinafter and while I have shown and will describe my preferred form of my device it will be understood that I do not limit myself to such preferred form but that various changes and adaptations may be made therein without departing from the spirit of my invention.

In the drawings accompanying and forming a part of this application:

Figure 1 is a side elevation of my device in its position of use.

Fig. 2 is a sectional view, partly in elevation, of one end of my device, on an enlarged scale.

Fig. 3 is a bottom plan of Fig. 2.

Referring to the drawings 5 is a rectangular block or base of wood or other suitable material provided at each end with 45 cut-away or recessed portions 6 and 7, and a groove 8 in its central portion.

Extending longitudinally and centrally of the recessed portions 6 and 7 are grooves or sockets 9 and 10, best shown in Fig. 2.

50 My wire holder comprises a base plate 11

of a thickness to substantially fill the recesses 6 and 7 and of a width and length corresponding to the dimensions of the said recesses, which base plate is secured positioned to block 5 by means of bolts 12. As 55 both of my wire holders are of the same construction only one will be described herein. Secured to the underside of base plate 11 by bolts 13 and 14 is a body member 15, tubular in transverse cross-section, 60 which is provided with upwardly extending bosses 16 and 17 of a length to properly space said body member from the base plate.

Extending centrally and longitudinally through body member 15 is a chamber 18 65 in which the end of the wire 19 is received. The upper portion of the rear end of body member 15 is cut away to form an extension of chamber 18 and a recess 20 is cut in plate 11 in register therewith for a purpose 70 hereafter explained. A set screw 21 in the upper side of body member 15 serves to hold the wire against displacement. Mounted in the groove 8 is a downwardly projecting spacing or bridging member 22 which 75 serves to bridge the space between the ends of the wires for the passage of the trolley wheel, and is of fiber or other suitable insulating material.

In the use of my device the wire holders 80 will first be removed from the block 5. The end of the wire will then be passed through chamber 18 until the end projects a suitable distance beyond the rear end of body member 15. It will then be bent upwardly and 85 then forwardly to lie upon the upper face of plate 11. The set screw 21 will then be tightened and the wire holder repositioned upon block 5. Suitable means will be provided for securing bridge member 22 in its 90 position of use.

Having described my invention what I claim is:

A circuit breaker terminal comprising a rectangular block; a recessed portion at 95 each end of said block; a groove extending longitudinally and centrally of each of said recessed portions; a groove extending longitudinally and centrally of said block between said recessed portions; and a wire 100

holder mounted in each of said recessed portions each comprising a base plate adapted to be mounted in said recessed portion; a body member secured to said base plate to extend parallel with said block; a longitudinally extending chamber in said body member; a connection from the rear end of said chamber to the groove

in the recessed portion of said block; and a bridge member mounted in the groove between said recessed portions. 10

In witness that I claim the foregoing I have hereunto subscribed my name this 20 day of September 1918.

GEORGE N. FREY.
